RETAINING CUP FOR LENSES AND THE LIKE

Robert Malcom, Chicago, Ill.

Application December 29, 1932, Serial No. 649,304

1 Claim. (Cl. 2-14)

My invention relates more especially to cups for receiving and holding lenses and involving means whereby the cups are firmly clamped to the body of the article, such as vizors, goggles and 5 the like.

The invention involves a continuous shell provided at one end with an inturned flange and the side walls of the shell upset into a pair of outwardly disposed flange portions between which 10 the material of the vizor or goggle is firmly clamped. That is to say, the invention involves a single piece element for holding the lens and for securing the cup to the vizor or other article.

The invention will be readily comprehended 15 from the following description of the accompanying drawing, wherein:

Figure 1 is a perspective view of a goggle provided with my improved lens holding cups.

Figure 2 is a cross sectional view of the lens 20 holding cup with a lens also in section; illustrating the initial condition of the cup.

Figure 3 is a similar view illustrating the final condition of cup with portions of the material of a goggle or vizor clamped by the cup wall.

In the particular exemplification I have shown 25 my invention as a lens holding cup secured to a goggle; although it will be understood that my improved cup may be used with vizors or other articles provided with sight-openings and that 30 perforated elements or screens may be employed instead of glass lenses.

In the drawing the wall or body 10 of the goggle may be of any suitable material provided 35 at proper points with annular sight openings.

My improved cups 11, 11 consist of cylindrical 40 shells of deformable material, preferably thin sheet metal, which are initially formed to provide an inturned flange 12 at one of the ends to form a seat for the lens or disc 13; while the 45 wall of each shell intermediate of the ends is formed with an outwardly disposed annular corrugation 14. This corrugation is preferably arranged substantially midway between the ends of the shell a distance removed from the lens-seat so as to provide sufficient metal between the corrugation and the opposite end of the shell as 50 shown at 15 in Figure 2.

The cup, formed as just described, with the lens 13 inserted in place as shown in Figure 2, is 55 then deformed, by suitable means, so as to slightly contract or reduce the diameter of the cup adjacent to the lens-seat as shown at 16 in Figure 3; while the walls or sides of the corrugation 14 are forced into parallel snug relation to provide the rearwardly sloping goggle or other material en-

gaging flange portion 17; and the end 15 of the cup folded inwardly parallel with the flange portion 17 into the outwardly opening material receiving annular channel or groove 18; with the perimetrical portion 19 flared outwardly. 5

It will be understood, of course, that before the cup forming shell is subjected to the operation whereby it is deformed into the final shape shown in Figure 3, the shell with the lens as shown in Figure 2 is inserted through suitable sight-openings in the vizor or goggle and that these openings are of size just sufficient to receive the inner ends of the shells, namely rearward of the corrugation 14, in order that the material 20 around the openings will be enfolded by the side 15 walls of the groove 18 when the walls of the shell are forced into the position described.

By employing thin sheet metal, the deforming condition shown in Figure 3 may be accomplished in a single operation, with the result that considerable time and labor heretofore required in forming lens holding cups and securing them in place will be eliminated; while at the same time the lens will not only be firmly held on its seat, but the cup will be securely fastened to the vizor, 25 goggle, or other article.

It will be seen that the diameter of the cup intermediate of the lens and the original corrugation 14 is slightly reduced as shown at 16 thereby maintaining the lens 13 against the flange 12. 30 By collapsing the side walls of the corrugation 14 toward each other into the rearwardly sloping flange portion 17, with the material 20 in the annular channel or groove 18 sloping forwardly, a firm gripping relation between the cup and 35 material is provided, whereby accidental removal of the cup is impossible.

My improved single piece eye-cup of thin sheet metal can be more quickly and cheaply made than heretofore has been the case, with the result 40 that a great saving in time and labor is obtained; and while I have shown and described the cup as especially adapted for securing lenses in place, it is apparent that it may be employed for other uses or purposes without, however, departing from 45 the spirit of my invention.

What I claim is:

A retaining cup of the character described comprising a single piece cylindrical shell composed of deformable metal provided at one end 50 with an inturned flange adapted to form a lens-seat, the diameter of the shell adjacent to said flange and rearward of the lens seat being reduced to provide an inwardly bowed portion whereby movement of the lens off its seat is pre- 55

vented, the cylindrical wall of the shell rearward of said bowed portion being expanded outwardly beyond the normal diameter of the shell and said portion collapsed inwardly upon itself in a reentrant manner and thence bent outwardly to provide an outwardly opening material receiving

groove disposed in a forwardly sloping manner while the perimeter of said end is flared outwardly and partially across the open end of said groove to provide an annular material gripping portion.

ROBERT MALCOM.
